(57) **CLAIM**

The ornamental design for a foldable chair, as shown and described.

DESCRIPTION

FIG. 1 is a perspective view of a foldable chair in an unfolded embodiment, the perspective view partially from the front side of the foldable chair, partially from the left side of the foldable chair, and partially from the top of the foldable chair; FIG. 2 is a front side view of the foldable chair of FIG. 1 in the unfolded embodiment;

FIG. 3 is a back side view of the foldable chair of FIG. 1 in the unfolded embodiment;

FIG. 4 is a right side view of the foldable chair of FIG. 1 in the unfolded embodiment;

FIG. 5 is a left side view of the foldable chair of FIG. 1 in the unfolded embodiment;

FIG. 6 is a top view of the foldable chair of FIG. 1 in the unfolded embodiment;

FIG. 7 is a bottom view of the foldable chair of FIG. 1 in the unfolded embodiment;

FIG. 8 is a perspective view of the foldable chair of FIG. 1 in a folded embodiment, the perspective view partially from the front side of the foldable chair, partially from the left side of the foldable chair, and partially from the top of the foldable chair;

FIG. 9 is a front side view of the foldable chair of FIG. 1 in the folded embodiment;

FIG. 10 is a back side view of the foldable chair of FIG. 1 in the folded embodiment;

FIG. 11 is a right side view of the foldable chair of FIG. 1 in the folded embodiment;

FIG. 12 is a left side view of the foldable chair of FIG. 1 in the folded embodiment;

FIG. 13 is a top view of the foldable chair of FIG. 1 in the folded embodiment; and,

FIG. 14 is a bottom view of the foldable chair of FIG. 1 in the folded embodiment.
